(57) **CLAIM**

The ornamental design for “VR glasses,” as shown and described.

DESCRIPTION

FIG. 1 is a rear perspective view of a pair of VR glasses; FIG. 2 is a front perspective view thereof; FIG. 3 is a front view thereof; FIG. 4 is a rear view thereof; FIG. 5 is a left side view thereof; FIG. 6 is a right side view thereof; FIG. 7 is a top view thereof; FIG. 8 is a bottom view thereof; FIG. 9 is a partial enlarged view of I in FIG. 1; FIG. 10 is a partial enlarged view of II in FIG. 5; FIG. 11 is a partial enlarged view of III in FIG. 5; and, FIG. 12 is a partial enlarged view of IV in FIG. 8. The broken lines in the figures depict portions of the VR glasses that form no part of the claimed design.
